UNITED STATES PATENT OFFICE.

GUSTAVE RADER, OF MONTCLAIR, NEW JERSEY.

PLASTER OR COMPOSITION BOARD.

No. 884,954.

Specification of Letters Patent.

Patented April 14, 1908.

Application filed February 21, 1908. Serial No. 416,996.

To all whom it may concern:

Be it known that I, GUSTAVE RADER, a citizen of the United States, residing at Montclair, in the county of Essex and State 5 of New Jersey, have invented certain new and useful Improvements in Plaster or Composition Boards, of which the following is a specification.

This invention relates to an improved 10 plaster-board for covering walls, ceilings, etc., which plaster-boards are made ready for use so that they can be directly applied to a wall or ceiling in such a manner that the wall-paper or other covering can be directly 15 pasted thereto without requiring a finishing coating for the plaster-boards; and for this purpose the invention consists of a plaster-board which comprises a layer of plaster of paris and a face-layer of paper which is united 20 with the layer of plaster of paris by means of projections or anchors made on the rear-side of the paper, as will be fully described hereinafter and finally pointed out in the claim.

25 In the accompanying drawings, Figure 1 represents a perspective view of my improved plaster-board, Fig. 2 is a horizontal section on line 2, 2, Fig. 1, and Fig. 3 is a perspective rear-view of the paper face-layer 30 or covering of the plaster-board.

Similar letters of reference indicate corresponding parts.

Referring to the drawings, *a* represents a 35 layer of plaster of paris which is mixed with suitable fibers, and *b* a face-layer of paper. The layer *a* is made in any suitable thickness and size, as required for the purpose to be used, while the face-layer of paper is roughened at its rear-surface so as to form projections or anchors *b*¹.

The projections or anchors *b*¹ are made on the rear surface of the paper by means of a wire-brush, toothed roller or other suitable means, in a quick and uniform manner. The 45 layer of plaster of paris and fibers is then cast over the roughened surface of the paper, so that the projections or anchors enter into the plastic body of plaster of paris and unite intimately therewith, whereby the reliable 50 connection between the body of the plaster

and the paper layer is obtained. The face-layer of paper imparts not only considerable strength to the plaster-board as it protects the same against injury and breakage while in transit or, when handled, but forms also a 55 smooth finish by which the finishing coat of plaster is dispensed with, so that the wall-paper or other covering can be applied directly to the face-paper and forms an intimate connection therewith. 60

Having thus described my invention, I claim as new and desire to secure by Letters Patent:

1. A plaster-board consisting of a layer of 65 plaster of paris, and a face-layer of paper united with the same by projections or anchors formed on the rear-side of the paper.

2. A plaster or composition board consisting of a layer of plastic material or composition and a face-layer of suitable fabric united 70 with the same by specially made integral projections or anchors formed on the rear side of the fabric.

3. A plaster or composition board consisting of a layer of plaster of paris and fiber, and 75 a face-layer of suitable fabric united with the same by specially made integral projections or anchors formed on the rear side of the fabric.

4. A plaster-board composed of a layer of 80 plastic material, and a face-layer of paper united by projections or anchors at its rear-side with the layer of plastic material.

5. A plastic-board consisting of a rear-layer of plaster of paris, and a face-layer of 85 paper united with the same by projections or anchors formed on the rear-surface of the paper.

6. A plaster-board consisting of a layer of 90 plaster of paris and fiber mixed, and a face-layer of paper united at its rear-side by means of projections or anchors with the layer of plaster of paris.

In testimony, that I claim the foregoing as my invention, I have signed my name in 95 presence of two subscribing witnesses.

GUSTAVE RADER.
